(57) **CLAIM**

The ornamental design for fishing reel portion, as shown and described.

DESCRIPTION

FIG. 1 is a first perspective view of a fishing reel with a fishing reel portion in accordance with our new design;

FIG. 2 is a second perspective view of the fishing reel with the fishing reel portion illustrated in FIG. 1;

FIG. 3 is a first side elevational view of the fishing reel illustrated in FIG. 1, with the fishing reel portion being hidden;

FIG. 4 is a second side elevational view of the fishing reel illustrated in FIG. 1, with the fishing reel portion being hidden;

FIG. 5 is a top plan view of the fishing reel illustrated in FIG. 1, with the fishing reel portion being hidden;

FIG. 6 is a bottom plan view of the fishing reel with the fishing reel portion illustrated in FIG. 1;

FIG. 7 is a rear elevational view of the fishing reel illustrated in FIG. 1, with the fishing reel portion being hidden;

FIG. 8 is a front elevational view of the fishing reel illustrated in FIG. 1, with the fishing reel portion being hidden;

FIG. 9 is a first enlarged, partial perspective view of the fishing reel with the fishing reel portion illustrated in FIG. 1;

FIG. 10 is a second enlarged, partial perspective view of the fishing reel with the fishing reel portion illustrated in FIG. 1;

FIG. 11 is an enlarged, partial bottom plan view of the fishing reel with the fishing reel portion illustrated in FIG. 1; and,

FIG. 12 is an enlarged, partial bottom plan view, similar to FIG. 11, of a fishing reel portion that identical to FIG. 1, but where both side boundaries of the fishing reel portion are shown in broken lines.

The broken line illustration of the environmental structure (the remaining structure of the fishing reel) in the drawings is not part of the claimed design.

In the fishing reel portion illustrated in FIG. 12, the side boundaries do not form part of the claimed design. In other words, with respect to the alternate design of the fishing reel portion illustrated in FIG. 12, it should be understood that the claimed design extends to the boundary but does not include the boundaries shown in broken lines.
